UNITED STATES PATENT OFFICE.

EDWARD E. PINKERTON, OF CHICAGO, ILLINOIS.

COLLAPSIBLE CRATE.

Application filed January 25, 1924. Serial No. 688,428.

To all whom it may concern:

Be it known that I, EDWARD E. PINKERTON, a citizen of the United States, and a resident of the city of Chicago, county of Cook, and State of Illinois, have invented certain new and useful Improvements in Collapsible Crates, of which the following is a specification.

My invention relates to improvements in collapsible crates, especially adapted for use in shipping various articles, and has for its object the provision of a simple and efficient construction of this character which is capable of economical manufacture.

Other objects will appear hereinafter.

The invention consists in the combinations and arrangements of parts hereinafter described and claimed.

The invention will be best understood by reference to the accompanying drawings forming a part of this specification, and in which—

Fig. 1 is a top plan view of a crate embodying the invention;

Fig. 2, a side view of the same;

Fig. 3, a perspective view of a collapsible body employed in the crate but showing a slightly different form of construction from that illustrated in Figs. 1 and 2;

Fig. 4, an enlarged section taken on line 4—4 of Fig. 2;

Fig. 5, a section taken on line 5—5 of Fig. 4;

Fig. 6, an enlarged section taken on line 6—6 of Fig. 2;

Fig. 7, a perspective view of a corner member employed for re-enforcing the body of the crate at the corners;

Fig. 8, a top plan view of the crate showing a modified form of construction for securing the parts together;

Fig. 9, an end view corresponding with Fig. 8, and

Fig. 10, a perspective view of another modified form of collapsible body employed in the crate.

The form of construction illustrated in Figs. 1, 2, 4, 5, 6 and 7 comprises a collapsible tubular body open at top and bottom and formed of the end walls 11 and the side walls 12 hingedly connected together at the corners so as to be capable of collapsing into flat form as indicated by the dotted lines in Fig. 3. The body 11—12 is preferably made of fibre board, corrugated paper, thin wood, or other comparatively

weak and, therefore, cheap material. Reinforcing members 13 in the form of angular metallic channel members are fitted over each corner of the body to re-enforce the same and metallic members 14 are also fitted centrally over the side walls 12 for the same purpose. Removable top and bottom members are associated with the body thus provided. The said top and bottom members each consists of strips 15 arranged to fit snugly over the walls 11—12 constituting re-enforcing and protecting flanges therefor. The body of each top and bottom member is composed of a number of longitudinal slats 16 nailed or otherwise secured to the strip 15 as shown. The top and bottom members are preferably composed of wooden strips which are comparatively thick and strong and sufficiently re-enforce and protect the body member 11—12 for shipping purposes. The top and bottom members are detachably held in place by means of pliable metallic strips 17 bent around the end strips 15 as shown. By this arrangement a simple, light and efficient shipping crate is provided which is capable of very economical manufacture.

In the form of body illustrated in Fig. 3 the re-enforcing members 13 and 14 are dispensed with and cloth re-enforcing members 18 glued to the outer sides of the wall members at each corner.

In the form of construction illustrated in Figs. 8 and 9 the top and bottom members are held in place by means of binding wires 19 instead of the strips 17.

The body member illustrated in Fig. 10 is made without re-enforcing members either at the corners or on the sides and the end walls are centrally creased at 20 to permit of inward folding thereof as indicated, thus permitting of the body being collapsed into more compact form.

While I have illustrated and described the preferred forms of construction for carrying my invention into effect, these are capable of variation and modification without departing from the spirit of the invention. I, therefore, do not wish to be limited to the precise details of construction set forth, but desire to avail myself of such variations and modifications as fall within the scope of the appended claims.

Having described my invention, what I claim as new and desire to secure by Letters Patent is:

1. A construction of the class described comprising a foldable body of comparatively weak material arranged to constitute the side walls of a crate; re-enforcing angular channel members fitting over the corners of said body; removable top and bottom members of comparatively strong material and having re-enforcing members fitting over said side walls; and means for securing said 10 top and bottom members in place on said walls, substantially as described.

2. A construction of the class described comprising a foldable body of comparatively weak material arranged to constitute the 15 side walls of a crate and folding at the corners to collapse into flat form; re-enforcing angular channel members fitting over the corners of said body; removable top and bottom members of comparatively strong 20 material and having flanges fitting over said side walls; and means for securing said top and bottom walls in place on said walls, substantially as described.

3. A construction of the class described 25 comprising a foldable body of comparatively weak material arranged to constitute the side walls of a crate; re-enforcing angular channel members fitting over the corners of said body; re-enforcing channel members 30 fitting over the side walls centrally; removable top and bottom members of comparatively strong material having re-enforcing members fitting over said side walls; and means for securing said top and bottom 35 members in place for said walls, substantially as described.

4. A construction of the class described comprising a foldable body of comparatively weak material arranged to constitute

the side walls of a crate and folding at the 40 corners to collapse into flat form; re-enforcing channel members fitting over the side walls centrally; removable top and bottom members of comparatively strong material and having re-enforcing members fitting over said side walls; and means for securing said top and bottom walls in place on said walls, substantially as described.

5. A construction of the class described comprising a foldable body of comparative 50 weak material arranged to constitute the side walls of a crate; wooden top and bottom members having flanges fitting over said side walls; and means for securing said top and bottom members in place on said 55 walls, substantially as described.

6. A construction of the class described comprising a foldable body of comparatively weak material arranged to constitute the side walls of a crate and folding at the 60 corners to collapse into flat form, the ends of said body being centrally creased to fold inwardly; removable wooden top and bottom members having flanges fitting over 65 said side walls; re-enforcing angular channel members fitting over the corners of said body; re-enforcing channel members fitting over the side walls centrally; and means for securing said top and bottom members 70 in place on said walls, substantially as described.

In testimony whereof I have signed my name to this specification in the presence of two subscribing witnesses:

EDWARD E. PINKERTON.
